UNITED STATES PATENT OFFICE

2,244,623

INTERNAL COMBUSTION ENGINE

Nelson M. Jones, Hatchville, Mass.

Application June 6, 1940, Serial No. 339,188

1 Claim. (Cl. 123—133)

This invention relates to an internal combustion engine and aims to provide a method and means whereby a medium is employed which has a definite refrigerating action or effect on the cooling system by changing from a liquid to a gaseous state and is thereafter used in the gaseous state as the power medium or fuel.

More specifically, it is aimed to employ a liquid hydrocarbon like butane or propane and supply it through an expansion valve into a coil in cooling relation to the liquid water cooling medium of the engine, from which coil, the gas is supplied to a mixing valve for admixture with air and subsequent ignition as the power medium.

The more specific objects and advantages will in part be pointed out and otherwise become apparent from a consideration of the description following taken in connection with accompanying drawings illustrating an operative embodiment.

In said drawings—

Figure 1 is a view primarily in central vertical section through one form of the invention;

Figure 2 is a detail enlarged vertical sectional view through the mixing valve structure;

Figure 3 is a horizontal section taken on the plane of line 3—3 of Figure 1, and

Figure 4 is a view partly in elevation and partly in section through a modified form.

Referring specifically to the drawings wherein like reference characters designate like or similar parts, an internal combustion engine is shown at 10 which for the most part is conventional. Such engine has a cylinder 11 in which a piston 12 is reciprocable and has a connecting rod 13 operatively connected to a crank 14 of the main shaft 15, suitably journaled within the crank case at 16. The cylinder 11 has a water jacket 17, an inlet duct 18 from which the fuel mixture is supplied to the cylinder in proper timed relation under control of a valve 19, the exhaust from the cylinder being under control of a properly timed valve 20 to escape through a pipe or duct 21 to the atmosphere or otherwise.

The space within the water jacket 17 is filled with water or other liquid cooling medium as at 22, which preferably contains an agent to prevent freezing thereof below any desired temperature, and such agent may be "Prestone," alcohol, glycerin or the like. Located within the cooling agent 22 is a coil 23 in communication with a fuel supply tank 24 by means of a pipe 25 including an expansion valve at 26.

In accordance with the invention, the fuel or

liquid supplied to the tank 24 is a liquid hydrocarbon which through passage through the expansion valve 26 becomes a vapor or gas and thus produces a distinct cooling or refrigerating effect on the liquid 22, as such gas passes through the coil 23.

The gas leaves coil 23 through a pipe 27 which conveys it to a mixing chamber 28 under control of a valve 29 and into which mixing chamber 10 28, air is admitted through a branch or port 30, under control of a throttle valve 31. Hence the gas and air will admix in the mixing chamber 28 and from the latter pass through the duct 18 into the cylinder 11 for firing or explosion by 15 any suitable means, the engine preferably operating on the four cycle principle.

Liquids which will act for refrigerating purposes and then as fuel as described and which are supplied to the tank 24, may be butane or propane.

It may be pointed out that the butane, propane or other liquid in the tank 24 produces its own pressure, the same varying up to one hundred and seventy pounds per square inch, the tank 24 being closed air tight, and no pumps being needed to place the butane or propane under pressure.

Various changes may be resorted to provided they fall within the spirit and scope of the invention. For example, I may use the modified form of Figure 4. In this form, in lieu of employing a coil in the water jacket of the cylinder, I employ a coil at 23' which is located within a reservoir 32, which is in communication with 30 the water jacket 17' of the engine by upper and lower pipes 33 and 34. The cooling liquid 22', similar to that used at 22 is in a quantity to fill the water jacket 17' and the tank 32 and pipes 33 and 34. In this form, the same fuel is used 35 as in the preceding form which is contained as a liquid in an air tight tank 24' and flows therefrom through a pipe 25' including an expansion valve 26' delivering into the coil 23' and from the latter, the gas following its cooling or refrigerating function, passes through a pipe 27', to a mixing valve device 28' similar to that shown in Figure 2 and employed in the first form, admixing with air therein and then passing through a pipe or duct 18' into the cylinder of the engine, 40 all remaining parts conforming in structure and operation to the first form.

Various other changes are permissible within the scope of the claim.

I claim as my invention:

In an internal combustion engine having a

cylinder and piston operable therein and a jacket about the cylinder for a cooling medium, a coil having a multiplicity of convolutions in said jacket and surrounding the cylinder, an expansion valve in line with the coil, means to supply liquid hydrocarbon to the expansion valve and

5 expand it under its own pressure directly into the coil as a gas for its refrigerating effect on the cooling medium, and means outside of the jacket to convey the gas from the coil and utilize it to drive the engine.

NELSON M. JONES.
